US0D1080569S

(12) **United States Design Patent** (10) **Patent No.:** **US D1,080,569 S**
(45) **Date of Patent:** **** Jun. 24, 2025**

(54) **TELEVISION**

- (71) Applicant: **Samsung Electronics Co., Ltd.**, Suwon-si (KR)
- (72) Inventors: **Sinwi Moon**, Suwon-si (KR); **Jangho Kim**, Suwon-si (KR); **Sangyoung Lee**, Suwon-si (KR); **Jinsu Park**, Suwon-si (KR); **Kyudae Lee**, Suwon-si (KR)
- (73) Assignee: **Samsung Electronics Co., Ltd.**, Suwon-si (KR)
- (**) Term: **15 Years**

(21) Appl. No.: **29/844,960**

(22) Filed: **Jul. 1, 2022**

(30) **Foreign Application Priority Data**

Jan. 4, 2022 (KR) 30-2022-0000217

(51) **LOC (15) Cl.** **14-03**

(52) **U.S. Cl.**

USPC **D14/126**

(58) **Field of Classification Search**

USPC D14/125, 126, 217, 239, 336, 371, 374, D14/448, 451; D20/10, 18, 19, 42

CPC G06F 1/1601; G06F 3/1446; G06F 2200/1612; H04N 5/64; G09F 9/3026

(57) **CLAIM**

The ornamental design for a television, as shown and described.

DESCRIPTION

FIG. 1 is a front perspective view of a television showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion in FIG. 1;

FIG. 10 is an enlarged view of the encircled portion in FIG. 3;

FIG. 11 is an enlarged view of the encircled portion in FIG. 3;

FIG. 12 is an enlarged view of the encircled portion in FIG. 5;

FIG. 13 is an enlarged view of the encircled portion in FIG. 5;

FIG. 14 is an enlarged view of the encircled portion in FIG. 6;

FIG. 15 is an enlarged view of the encircled portion in FIG. 7;

FIG. 16 is an enlarged view of the encircled portion in FIG. 7;

FIG. 17 is an enlarged view of the encircled portion in FIG. 8;

(Continued)

FIG. 18 is an enlarged view of the encircled portion in FIG. 8;

FIG. 19 is an enlarged view of the encircled portion in FIG. 8; and,

FIG. 20 is an enlarged view of the encircled portion in FIG. 8.

The evenly-dashed broken lines in the figures depict portions of the television which form no part of the claimed design.

The dot-dash lines depict the limits of the enlarged views and form no part of the claimed design.

1 Claim, 20 Drawing Sheets
